UNITED STATES PATENT OFFICE.

MATT STROM AND ERICK HOGLUND, OF DULUTH, MINNESOTA.

SOIL-CULTIVATING TOOL.

1,416,906.

Specification of Letters Patent. Patented May 23, 1922.

Application filed March 8, 1921. Serial No. 450,595.

To all whom it may concern:

Be it known that we, MATT STROM and ERICK HOGLUND, citizens of the United States and of Russia, respectively, both residing at Duluth, in the county of St. Louis and State of Minnesota, have invented certain new and useful Improvements in Soil-Cultivating Tools, of which the following is a specification, reference being had therein 10 to the accompanying drawing.

This invention relates to improvements in rotary soil cultivating tools, such as disclosed in our United States Patent No. 1,155,289 of September 28th, 1915, and has 15 special reference to novel means for holding in operative position the two part blades employed in such cultivators.

The principal object of our present invention is to provide more simple and practical 20 means for holding the sections of the blades in their respective position upon the rotating shafts of the cultivator.

Other objects and advantages of the invention will appear in the further description 25 thereof.

Referring to the accompanying drawing forming part of this application and in which like reference characters indicate like parts:

30 Figure 1 is a vertical sectional view through a fragmental portion of a tool supporting shaft having two of our improved hubs mounted thereupon;

Figure 2 is a side elevation of one of the 35 hubs with the soil cultivating blade removed;

Figure 3 is a side elevation of the inside face of one side of one of the hubs;

Figure 4 is a side elevation of the inside 40 face of one side of one of the hubs, showing the blades arranged at a different angle in relation to the shaft;

Figure 5 is a side elevation of one of the blades attached within the hub; and

45 Figure 6 is an edge elevation of one of the blades apart from the hub.

The separable hubs each comprise two like halves 1 and 2, mounted upon the square rotative cultivator shaft 8. These halves are 50 alike in form and are provided with diametrically disposed cut-away portions 3 in the cooperative faces thereof, said portions being the exact width of the shanks 4 of the

blades 5, and when the halves are assembled upon the shaft 8 the cut-away portions 3 55 are arranged diametrically opposite so that the blades assembled in one half extend diametrically opposite to those in the other half. Each pair of blades are carried in their respective halves and abut the shaft 8 either 60 squarely or on one side thereof, or on the corner as shown in Figures 3 and 4.

The shank 4 of each blade 5 is provided, as by drop forging, (they being wrought blades), with a concavo-convex tit 7, the convex portion of which when assembled intermediate of the halves of the hub register with the concaved recess 9 in one half, while the concaved portion of the tit registers with a convex portion or tit 6 formed in the cut-away portion of the opposite half, thus each blade is firmly held in the cut-away portion intermediate of the halves and positively by both halves, said halves having no registerable portions. 75

Having thus described our invention, what we claim and desire to secure by Letters Patent is:

1. The combination with a two part hub of the class described having diametrically 80 disposed recesses in each half thereof, of two part blades having shanks registerable within said cut-away portions, said shanks being provided with concavo convex tits thereupon registerable within depressions in one half 85 and tits within the other half.

2. The combination with a two part hub of the class described having diametrically disposed recesses in each half thereof, of two part blades having shanks registerable within 90 said cut-away portions, said shanks being provided with concavo convex tits thereupon, tits within the cut-away portions of one half registering with the concave portion of the tits in the blade and recesses 95 within the non cut-away portions of the other half for registration with the convex portion of the tits in the blade.

3. The combination with a two part cultivator hub of the character described each 100 part having a diametrically disposed cut-away portion non-registerable with the portion in the other part, of opposed recesses and tits in the cooperative faces of the two parts, and two part blades having shanks 105 provided with concavo convex tits therein

which are cooperatively engaged with the recesses and tits in the parts of the hub when united, whereby the shanks of each pair of blades are housed only in one part 5 of the hub but held positively against dislodgment by both parts thereof.

In testimony whereof we hereunto affix

our signatures in the presence of two witnesses.

MATT STROM.
ERICK HOGLUND.
